UNITED STATES PATENT OFFICE.

JOHN BRIDGES, OF LEON, IOWA, ASSIGNOR OF TWO-THIRDS TO THOMAS A. McGREW, OF SAME PLACE.

WATER-INDICATOR FOR BOILERS.

SPECIFICATION forming part of Letters Patent No. 235,409, dated December 14, 1880.

Application filed October 19, 1880. (No model.)

To all whom it may concern:

Be it known that I, JOHN BRIDGES, of Leon, in the county of Decatur and State of Iowa, have invented a new and Improved Water-5 Indicator for Boilers, of which the following is a specification.

The object of this invention is to provide a simple and effective device for automatically regulating the height of water in a steam-boiler.

The invention is an improvement upon the water-governor for which Letters Patent No. 218,922 were issued to me August 26, 1879; and it consists of a novel construction and arrangement of float, pipes, levers, and an indicator, in combination with the water-supply tank, feed-pump, and boiler, all of which is hereinafter set forth.

Figure 1 is a plan of the device with parts 20 broken away to exhibit other parts. Fig. 2 is a side elevation of the same, partly in section, and with parts broken away to exhibit other parts.

Similar letters of reference indicate corresponding parts.

In the drawings, A represents the boiler, the water-line of which is indicated at a. B C represent two covered tanks set on supports D on top of the boiler A. Said tanks B C are 30 centrally divided by vertical diaphragms B' C', respectively, that have openings b c through them for the passage of the levers G K, that are respectively fulcrumed on the lower edges of said openings b c; and said tanks B C are 35 designed to be filled, the one B with steam or hot water by means of its connection by the pipe F with the boiler A, and the other, C, with cold water by means of its connection with pump S.

40 A float, E, rests on the water a in the boiler A, and its rod E' projects upward through the vertical pipe F, leading from the tank B to the boiler A, into said tank B, and there connects by a loose joint, as shown at d, with the lever G, which lever G passes through the opening b into the other part of the tank B, and is there rigidly connected with the crank-shaft H, which is journaled in the sides of said tank B, and extends horizontally out through said 45 tank B, and has rigidly secured on its outer

end a crank, H', the function of which is hereinafter described. Corresponding with the shaft H is a crank-shaft, I, journaled in the sides of the tank C, and extending horizontally from it, and having on its outer end a rigid 55 crank, I', whose use is hereinafter set forth. Rigidly secured to this crank-shaft I is a lever, K, that extends through the opening c and is fulcrumed on the lower edge thereof, and is connected at its other end to the stirrup L, that rigidly holds the ends of the valve-rod L' of the rotating valve M, which turns in the cylinder M', that is provided with an opening, f, said cylinder M' being within the tank B and communicating with a pipe, N, that 60 extends through a side of the tank B into the water-supply tank O.

The cranks H' I' are connected, by their respective crank-pins g h, with opposite ends of the lever P, that extends horizontally along 70 the sides of the tanks B C, and is fulcrumed in the standard P', that is secured to the support D, and the longer end of this lever P connects, by means of rod or chain Q, with a pointer, R', that is pivoted on the face of a 75 dial, R, so that the movements of said lever P are indicated or registered on said dial R.

S represents a force-pump, from which a suction-pipe, S', extends to the supply-tank O, and from which a feed-pipe, T, extends to the 80 boiler A, while an overflow-pipe, U, taps the pipe T and extends upward to the tank C. The tank O being filled with water, the force-pump S is put in motion, and, drawing the water through the suction-pipe S', forces it into 85 the boiler through the feed-pipe T, that is provided with a check-valve, m, and into the tank B through the overflow-pipe U.

As the water rises in the boiler A the float E also rises, and by means of its connections—the rod E', levers G K, shaft and crank H H', lever P, crank and shaft I I', stirrup L, and valve-rod L'—causes the valve M to open the opening f in the cylinder M' and permit water to flow from said tank C into the supply-tank 90 O, and consequently less water enters the boiler A; and when the water in the boiler subsides, the consequent falling of the float E causes the valve M to close the opening f, so that the pump S shall throw more water into 95 100

the said boiler A, and thus when the float E, and its connections, as hereinbefore described, is once correctly adjusted it governs the water-supply to the boiler with perfect and constant accuracy, so that the water-line a will vary only within very narrow limits. The moving of the float E also causes the pointer R' to move over the face of the dial R and indicate the level of the water in the boiler A. Thus it will be seen that the pump may be continued always in motion and pumping water without danger of ever forcing a surplus into the boiler; and it is also obvious that if the pump be kept in motion the amount of water in the boiler cannot fall below the point of safety; that a regular, constant, and sufficient supply must result from the application of this device.

Having thus described my invention, I claim as new and desire to secure by Letters Patent—

A water-governor constructed substantially as herein shown and described, consisting of tanks B C, float E, rod E', lever G, shaft and crank H H', lever P, crank and shaft I' I, lever K, stirrup and valve-rod L L', valve M, cylinder M', provided with opening f, pipe N, supply-tank O, pump S, suction-pipe S', feed-pipe T, provided with check-valve m, and overflow-pipe U, arranged and operated as set forth.

JOHN BRIDGES.
